UNITED STATES PATENT OFFICE

138,850

DESIGN FOR A COMBINED DRILL AND CUTTER

Harry C. Wilson, Beverly Hills, Calif., assignor to Robert H. Clark, Los Angeles, Calif.

Application June 26, 1944, Serial No. 114,203

Term of patent 14 years

(Cl. D54—14)

To all whom it may concern:

Be it known that I, Harry C. Wilson, a citizen of the United States residing in the city of Beverly Hills, county of Los Angeles, and State of California, have invented a new, original, and ornamental Design for a Combined Drill and Cutter, of which the following is a specification, reference being had to the accompanying drawing, forming a part thereof.

Fig. 1 is a perspective side view of a combined drill and cutter embodying the design of the present invention, and Fig. 2 is a bottom end view of the combined drill and cutter.

I claim:

The ornamental design for a combined drill and cutter, as shown.

HARRY C. WILSON.
